UNITED STATES PATENT OFFICE.

CHARLES B. LOVELESS, OF WARREN, OHIO, ASSIGNOR TO THEODOR KUNDTZ, OF LAKEWOOD, OHIO.

FOLDING CHAIR.

1,176,915.

Specification of Letters Patent.

Patented Mar. 28, 1916.

Application filed January 7, 1915. Serial No. 1,037.

To all whom it may concern:

Be it known that I, CHARLES B. LOVELESS, a citizen of the United States of America, residing at Warren, in the county of Trumbull and State of Ohio, have invented certain new and useful Improvements in Folding Chairs; and I hereby declare the following to be a full, clear, and exact description of the invention, such as will enable others skilled in the art to which it pertains to make and use the same.

This invention relates to improvements in folding chairs, and one object of this invention is to produce a folding-chair construction the component parts whereof can be assembled with facility and when assembled are not liable to become displaced.

Another object is to construct a folding chair which is strong and durable and can be stored in a small space when in a collapsed or folded condition.

With these objects in view, this invention consists in certain structural features and combinations of parts hereinafter described in this specification, pointed out in the claims, and illustrated in the accompanying drawings.

In said drawings, Figure 1 is a side view, in central vertical section, of a folding chair embodying my invention. Fig. 2 is a side view, in central vertical section, showing said chair in a collapsed or folded condition. Fig. 3 is a rear elevation of a folding chair embodying my invention. Fig. 4 is a transverse section in detail, the section being taken along the line 4—4, Fig. 1, through the leg-forming lower portion of one of the outer side pieces of the chair. Portions are broken away in Figs. 2 and 3 to more clearly show the construction.

As shown in Figs. 1 and 3, my improved folding chair comprises a pair of laterally spaced rearwardly inclined upright wooden outer side pieces A which have the lower portions thereof forming the forwardly extending legs of the chair and their upper portions participating in the formation of the back of the chair.

A pair of laterally spaced rearwardly extending wooden legs B are arranged between and cross the lower leg-forming portions of the side pieces A.

A horizontally arranged seat C rests on the upper ends of the legs B, as shown in Figs. 1 and 3, and extends between the outer

side pieces A and is pivoted to said side pieces, as at 5, horizontally and transversely of the chair. The seat C is provided, at its under side (see Figs. 1 and 3) with metal plates 6 arranged next forward of the upper ends of said legs.

The upper portions of the side pieces A are connected together by cross-bars 7 which participate in the formation of the back of the chair and the leg-forming lower portions 65 of said side pieces are tied together near their lower ends by a cross-bar 8. The rearwardly extending legs B are tied together by cross-bars 10.

A horizontally arranged pivotal rod D, 70 which is parallel with the axis of the seat C, extends, as shown in Figs. 1 and 3, through the rearwardly extending legs B where said legs cross the leg-forming lower portions of the outer side pieces A and extends through said portions of said outer side pieces, and a spacing collar E is loosely mounted on said rod between the leg-forming lower portion of each side piece A and the adjacent leg B. It will be observed 75 therefore that the rearwardly extending legs B are not only arranged between the leg-forming lower portions of the outer side pieces A but spaced from said side pieces, and that each leg B is pivoted to the leg-forming lower portion of the adjacent outer side piece A horizontally and transversely 80 of the chair.

A wrought metal link G is instrumental in connecting each rearwardly extending leg B 90 with the leg-forming lower portion of the adjacent outer side piece A and is arranged below the rod D, and said portion of said outer side piece is provided, a suitable distance below said rod but above the cross-bar 8, with a slot which is arranged longitudinally of said side piece and extends, as at 12, from the rear edge or surface of said side piece forwardly to a point substantially central between said edge or surface and the forward edge or surface of said side piece and extends from said point, as at 13, laterally and inwardly to the inner side of said side piece.

Each link G extends along the outer side 105 of the adjacent rearwardly extending leg B and terminates at its rear end in a pivotal member 14 which extends into said leg and is parallel with the axis of the seat C, and hence said link is pivoted to said leg hori- 110

zontally and transversely of the chair. Each link G also extends along the inner side of the adjacent outer side piece A and (see Figs. 1, 3 and 4) terminates at said side piece in 5 a laterally and outwardly extending arm 15 which projects at the upper end of the forward portion 13 of the slot in said side piece from the inner side of said side piece into said portion of said slot and has its outer 10 end-portion 16 projecting within the rear portion 12 of said slot rearwardly beyond the aforesaid forward portion of said slot so that said link is held in suitable connection with said side piece without any unsightly projection or exposure of said end-portion of said arm of the link at the exterior side of said side piece.

Fig. 2 shows my improved folding chair in a collapsed or folded condition, and it will 20 be observed that in the relative position of the parts of the folded chair the link-arms 15 and their rearwardly projecting members 16 are at the lower ends of the slots in the leg-forming lower portions of the outer side 25 pieces A.

By the construction hereinbefore described it will be observed that the component parts of my improved folding chair can be assembled with facility; that the 30 spacing of the rearwardly extending legs B through the medium of the collars E from the outer side pieces A is important to permit the arrangement of said links relative to the connecting parts as hereinbefore described; that the room taken up by the chair in the collapsed or folded condition of the 35 chair is reduced to a minimum; that the parts when assembled are not liable to become disconnected, and that the construction is simple, strong and durable.

What I claim is:—

1. In a folding chair, the combination, with two crossed legs pivotally connected together, one leg being provided with a slot 45 which is arranged longitudinally of the leg

and has a portion thereof extending to a point substantially central between the rear and forward edges or surfaces of the leg from one of said edges or surfaces and also has a portion extending from said point 50 to one side of the leg, of a link pivotally connected at one end to the other leg and extending between the legs and terminating at its opposite end in an arm which projects at the upper end of the aforesaid slot into 55 the second-mentioned portion of the slot and has its outer end-portion projecting within the first-mentioned portion of said slot from the second-mentioned portion of the slot.

2. In a folding chair, the combination, 60 with a forwardly extending leg, and a rearwardly extending leg spaced from and crossing the first-mentioned leg, said legs being pivotally connected together, the forwardly extending leg being provided with a slot 65 arranged longitudinally of said leg, which slot has its rear portion extending forwardly from the rear edge or surface of said forwardly extending leg and has its forward portion extending to the inner side of said leg, of a link extending between the legs and along the outer side of and pivotally connected to the aforesaid rearwardly extending leg, said link also extending along the inner side of the aforesaid forwardly extending leg and there terminating in an arm 75 which projects at the upper end of the aforesaid slot into said slot from said side of said forwardly extending leg and has its outer end-portion projecting within the rear portion of said slot rearwardly beyond the aforesaid forward portion of the slot.

In testimony whereof, I sign the foregoing specification, in the presence of two witnesses.

CHARLES B. LOVELESS.
